CLAIM

The ornamental design for a display screen or portion thereof with graphical user interface, substantially as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with a graphical user interface in accordance with an embodiment; and,

FIG. 2 is a front view of a display screen or portion thereof with a graphical user interface in accordance with an embodiment.

The outermost broken lines illustrate a display screen or portion thereof and form no part of the claimed design. The

(Continued)

remaining broken lines, illustrating portions of the graphical user interface, form no part of the claimed design.
